UNITED STATES PATENT OFFICE

JOSEPH E. MARQUIS, OF LYNN, MASSACHUSETTS

HEEL-TRIMMING MACHINE

Application filed January 7, 1928. Serial No. 245,101.

This invention relates to heel-trimming machines and particularly to machines that are designed for trimming the leather lift which is usually attached to the bottom of a wooden heel. In trimming this leather lift it is desirable to not only trim the edge of the lift so that it will conform to the shape of the wooden heel but also to chamfer the corner of the lift somewhat so that the bottom 10 of the heel may be sanded or burnished without injuring or disturbing the bead which is rolled on the edge of the heel. My present invention provides a novel mechanism for thus trimming the leather lift of the wooden heel and chamfering the edge.

In order to give an understanding of the invention I have illustrated in the drawings a selected embodiment thereof which will now be described after which the novel features 20 will be pointed out in the appended claims.

Fig. 1 is a front view of a heel-trimming machine embodying my invention with a part broken out;

Fig. 2 is a top plan view of Fig. 1;

Fig. 3 is an end view showing the support against which the heel rests during the trimming operation;

Fig. 4 is a section on the line 4—4, Fig. 5;

Fig. 5 is a fragmentary section on the line 30 5—5, Fig. 1;

Fig. 6 is a perspective view of a heel with the leather lift attached and before it is trimmed;

Fig. 7 is a somewhat diagrammatic view illustrating the operation of the trimming cutters;

Fig. 8 is a fragmentary perspective view of a heel after it has been trimmed;

Fig. 9 is a side view of the heel after it 40 has been trimmed and after the bead has been rolled on it;

Fig. 10 is a section on the line 10—10, Fig. 5.

Before describing the machine I will refer briefly to the operations performed thereby. In Fig. 6, 1 indicates a wooden heel such as is used on women's shoes and 2 is a leather lift which is nailed to the bottom of the heel. The leather lift when first attached to the heel is somewhat larger than the heel so that the edge of the lift projects beyond the per-

ipheries of the heel as shown at 3. This projecting edge 3 has to be trimmed off so as to make the outline of the leather lift 2 correspond to the outline of the heel.

It is also desirable to chamfer the corner 55 of the lift 2 as shown at 4 so that when the bottom face 5 of the lift is subsequently polished or sanded the polishing or sanding instrument will not injure or disturb the bead 6 which is usually formed on the heel before 60 it is finished.

In the present embodiment the edge 3 of the leather lift is trimmed to the contour of the heel by means of a rotary trimmer as usual in devices of this type and I also employ a rotary cutter of special shape for chamfering the corner of the lift as shown at 4. The rotary cutter by which the edge 3 of the heel lift is trimmed is indicated at 7. This cutter is mounted upon a shaft 8 which is journaled 70 in bearings 9 carried by the frame 10, said shaft being provided with the driving pulley 11 by which it may be driven. The heel which is being trimmed is supported against a work-supporting plate 12 which is mounted on a block or rest 13, the latter being carried by a bracket arm 14. This bracket arm in turn is adjustably secured to a support 15 which is secured to the frame.

The bottom face 5 of the leather lift 2 of the heel is held against the work-supporting plate 12 by the operator and in such position that the rotary trimmer 7 will act on the edge of the lift and trim the latter to a contour corresponding to that of the heel 1 as 85 the heel is turned about its axis by the operator. During this operation the heel is held horizontal with the face 5 in a vertical plane as clearly seen in Fig. 5.

Associated with the cutter 7 is a guard 16 which protects the cutter and prevents the operator from becoming injured thereby. This guard 16 also acts as a guide for the heel, the lower end of the guard resting against the outer face of the heel as shown in Fig. 5. 95 The guard is of usual construction and it is adjustably carried by a support 17 which is rigid with an arm 18 that extends from the supporting member 15. The guide is fitted in ways 19 in the support 17 and is adjustable 100

vertically in the ways by an adjusting screw 20, and its lateral position is determined by a stop screw 21, all as usual in devices of this character.

5 The cutter 7 rotates in the direction of the arrow Figs. 5 and 7 and, therefore, the cutting action of the cutter on the lift 2 is in a direction from the wooden heel toward the bottom surface 5. This trimming operation leaves a feather edge as shown at 22 which it is necessary to trim off in order to complete the trimming operation. According to my invention the trimming of this feather edge 22 is accomplished by means of a rotary cutter which co-operates with the cutter 7 and which trims the feather edge so as to form the chamfer 4 around the corner of the heel. This second rotary cutter is of the cylinder type and it is indicated at 23, it having the 10 cylindrical cutting edge 24. The cutter 23 is fast on a shaft 25 which is journalled in a bearing 26 adjustably carried by the block 13, said cutter being preferably driven from the shaft 8. For this purpose the shaft 8 has a pinion 27 thereon which meshes with 15 a gear 28 on the shaft 25.

The chamfering cutter 23 is so disposed with relation to the cutter 7 that as the heel is turned about its axis to cause the cutter 7 20 to operate progressively from one corner 29 of the lift 2 around the back of the heel to the other corner 50, the cutting edge 24 will act on the corner of the heel just in the rear of the cutter 7 and in so doing will trim the 25 feather edge 22 from the heel as shown in Figs. 4 and 7 thus leaving the heel with the chamfered corner 4. The turning movement of the heel thus feeds the leather lift to both cutters 7 and 23 and as both cutters are rotary cutters the trimming operation is easily and quickly done.

After the heel has been trimmed as shown in Figs. 8 and 9 then the edge of the lift 2 is rolled or burnished thereby to form thereon the bead 6 and subsequent to the forming of the bead the bottom of the heel is sanded or polished. Owing to the manner in which the heel is trimmed the bead will be formed at the corner 30 so that the face 5 will be 50 situated slightly beyond the bead. Consequently the polishing or sanding of the face 5 in the further treatment of the heel can be accomplished without effecting, injuring or destroying in any way the bead 6.

55 In the operation of the device it is important that the plane of the face or work-supporting plate 12 should be at the proper angle so that the trimmed face of the leather lift 2 will conform to the curvature and angle 60 of the outside of the heel. Wooden heels are made in different shapes and the angle between the face 5 of the leather lift and the side face of the heel varies somewhat in different styles of heel. This makes it necessary to adjust the face plate 12 so that it

may have different angular relations. As shown in Fig. 5 the face plate stands substantially vertically but for some heels it may be desirable to have it incline slightly to the vertical. The connection between the 70 block 13 and its supporting bracket 14 is one which permits such adjustment.

The block 13 is provided with a screw-threaded stem 31 which extends through an opening in the bracket arm 14, said block 75 being clamped to the arm by means of a thumb nut 32 which is screw threaded to the stem. By loosening the nut 32 the block 13 may be turned about its stem 31 to vary the angle of the face against which the bottom 80 of the heel rests.

Since the stem 31, which is the axis about which the block 13 is adjusted, is located below the shaft 25, the tilting of the block above described will tend to shift the position of the gear 28 relative to the gear 27. I have, therefore, provided means for compensating for this shift of position so as to maintain the gears in proper mesh for any position in which the block 13 may be adjusted. This is provided for by adjustably connecting the supporting arm 14 to the main support 15. As shown in Fig. 3 the arm 14 extends through an extension 33 on the member 15 and is adjustable horizontally, it being retained in any adjusted position by a clamping screw 34.

The adjustment of the block 13 can be effected by an adjusting screw 35 which screw threads through a boss 36 formed on the extension 33 and has a swivel connection with the block 13 as shown at 37. If in adjusting the block 13 into a new angular position the gear 28 is separated from the gear 27 then the block may be bodily adjusted laterally 105 to the left in Fig. 3 or toward the observer in Fig. 1 thereby bringing the gears properly in mesh again. On the other hand, if the adjustment is such as to cause the gears to bind then the block 13 may be adjusted bodily 110 to the right Fig. 3 or away from the observer in Fig. 1 so as to prevent any binding action.

In effecting such adjustment the set screw 34 will be loosened and the position of the block 13 may then be shifted by operating 115 the screw 35, the set screw 34 being tightened again when the proper adjustment has been made.

The bearing 26 for supporting the shaft 25 is shown as adjustably secured to the block 120 13. This bearing is provided with a depending stem 38 which is provided with a hole 39 to receive a clamping screw 40 which screws into the block 13. The hole 39 is larger than the screw 40 so as to provide 125 for vertical and lateral adjustment and the stem 38 is retained in adjusted position partly by the clamping action of the clamping screw 40 and partly by the positioning set screw 41, 42 which engage the bottom and side of 130

the stem 38. The set screw 41 is screw threaded through an ear 43 on the block 13 and the set screw 42 is screw threaded through a second ear 44 which is secured to and extends from the block 13.

5 While I have illustrated herein a selected embodiment of my invention I do not wish to be limited to the constructional features shown.

10 I claim:

1. In a heel-trimming machine, the combination with a heel rest to receive the bottom of the heel to be trimmed, of a rotary cutter for trimming the peripheral edge of the heel progressively, and a second rotary cutter situated non-axially of the first-named rotary cutter for simultaneously chamfering the corner of the heel.

2. In a heel-trimming machine, the combination with a heel rest having a vertical face to receive the bottom of the heel to be trimmed, of a rotary cutter for trimming the peripheral edge of the sides and back of the heel progressively, and a second rotary cutter 25 rotatable about an axis separate from but parallel to that of the first cutter and adapted to simultaneously chamfer the corner of the heel at the sides and back.

3. In a heel-trimming machine, the combination with a heel rest, of a rotary cutter adapted to act on the periphery of the heel as the latter is turned thereby to progressively trim the heel around its periphery, and a second rotary cutter operatively connected 35 to the first cutter but rotating about a different axis from that of the first-named cutter and adapted to chamfer the corner of the heel.

4. In a machine for trimming a leather lift 40 attached to the bottom of a wooden heel, the combination with a heel support against which the bottom of the heel is placed, of a rotary cutter for trimming the leather lift progressively around the periphery of the heel as the latter is turned, and a cylindrical cutter for chamfering the edge of the leather lift.

5. In a machine for trimming a leather lift attached to the bottom of a wooden heel, the 50 combination with a heel support against which the bottom of the heel is placed, of a rotary cutter for trimming the leather lift progressively around the periphery of the heel as the latter is turned, a cylindrical rotary cutter for chamfering the edge of the heel, and means to operate the cylindrical cutter from the first-named cutter.

6. In a machine for trimming a leather lift attached to the bottom of a wooden heel, the 60 combination with a rest against which the bottom of the heel is placed, of a rotary cutter for acting progressively on the edge of the leather lift as the heel is turned on the rest thereby to trim said lift to conform to 65 the contour of the heel, a rotary cutter for

chamfering the edge of the heel, said cutters rotating about different axes and driving connections between the two cutters, said rest being tiltable to permit the first-named cutter to conform to different shapes of heel.

7. In a heel-trimming machine for trimming the periphery of a leather lift attached to the bottom of a wooden heel, the combination with a heel rest by which the heel is positioned, of a rotary cutter for trimming the periphery of said lift progressively as the heel is turned, a second rotary cutter for chamfering the corner of the heel as it is trimmed, gearing connecting said cutters, said heel rest being tiltable to permit the cutter to conform to different shapes of heel, and also being bodily adjustable to enable the gearing to maintain operative engagement in different angular positions of the heel rest.

80 In testimony whereof, I have signed my name to this specification.

JOSEPH E. MARQUIS.
